(57) **CLAIM**

We claim the ornamental design for binoculars, as shown and described.

DESCRIPTION

FIG. 1 is an isometric view of binoculars, according to one embodiment;

FIG. 2 is a top plan view of the binoculars of FIG. 1;

FIG. 3 is a left side view of the binoculars of FIG. 1;

FIG. 4 is an eyepiece-end elevation view of the binoculars of FIG. 1;

FIG. 5 is a bottom plan view of the binoculars of FIG. 1; and, FIG. 6 is an objective-end elevation view of the binoculars of FIG. 1.

In the figures, the broken lines showing strap-attachment loops are illustrative of environmental structure that forms no part of the claimed design.
